UNITED STATES PATENT OFFICE.

WILLIAM K. AUCHINCLOSS, OF NEW YORK, N. Y., ASSIGNOR TO CORNELIUS VANDERBILT, OF NEW YORK, N. Y.

RAILWAY-CAR.

SPECIFICATION forming part of Letters Patent No. 727,876, dated May 12, 1903.

Application filed October 9, 1902. Serial No. 126,379. (No model.)

To all whom it may concern:

Be it known that I, WILLIAM K. AUCHINCLOSS, a citizen of the United States, and a resident of the borough of Manhattan, city and State of New York, have invented certain new and useful Improvements in Railway-Cars, of which the following is a specification.

My invention relates to railway-cars, the principal part of the framework of which is composed of rolled or pressed metal and comprises the features hereinafter set forth and claimed.

In the drawings which accompany this specification, Figure 1 is a central longitudinal section of one half of a car embodying my invention, the other half being exactly similar thereto. Fig. 2 is a detail plan view. Fig. 3 is a half-end elevation, and Fig. 4 is a half-section through the bolster.

While the present invention is shown as applied to a hopper-bottom car, it is obvious that it is not limited to such cars, but may be used with other forms of cars, as flat-cars, gondola cars, box-cars, &c.

In the car illustrated, 11 are the center sills, preferably channels of rolled metal. These sills extend from bolster to bolster. To the inner surfaces of these sills I secure, as by rivets, the spacing-blocks 2. These blocks may be made of cast-steel, and in the form shown are box-like in structure, having four walls or sides, open ends, and a central transverse partition. They are preferably located at the bolster, as shown, and form a part thereof. Draft-rigging sills 3 are secured to the inner walls of the blocks 2 and extend therefrom to the ends of the car. The bolster center-bearing piece 4 is then secured between the sills 3, thus obtaining a very strong framework for supporting the weight of the car and for receiving and transmitting the end thrusts to which the car is subjected.

It has been customary heretofore either to run the center sills the full length of the car and secure the draft-rigging thereto or else to secure draft-rigging sills directly to the center sills. By the insertion of spacing-blocks, however, between the draft-rigging and center sills I am enabled to space the draft-rigging sills the usual distance apart and to greatly increase the distance between the cen-

ter sills. This feature is of great advantage when one wishes to utilize the space between these sills as a part of the car-body. For example, in the hopper-bottom car shown I am thereby enabled to place large hopper-doors between the center sills, and by inclining the floor-plates toward said doors I utilize the space between the sills and so dispense with a central longitudinal peak above them and hopper-doors on either side thereof, as in previous constructions.

The bolster-beams 5, which are placed above the sills 1 and 3, are riveted to the spacing-blocks 2 (see Fig. 4) and also by means of channels 6 to the sills 3, thereby increasing the rigidity of the united parts.

The bolster comprises side pieces 7, which may be of any approved form. They are secured at their inner ends to the sills 1 and spacing-blocks 2 by rivets which pass through the web of the said sills and the side walls of the blocks 2. The outer ends of the parts 7 are secured to the side sills 8.

What I claim, and desire to secure by Letters Patent, is—

1. In a metallic car-frame, a longitudinal center sill, a draft-rigging sill, and a spacing-block between the overlapping ends of said sills, substantially as described.

2. In a metallic car-frame, longitudinal center sills, draft-rigging sills, and spacing-blocks between the ends of said center sills and the overlapping rear ends of said draft-rigging sills, substantially as described.

3. In a metallic car-frame, longitudinal center sills, draft-rigging sills, a bolster center-bearing piece secured between said draft-rigging sills, and spacing-blocks between the center sills and the overlapping rear portion of the draft-rigging sills, substantially as described.

4. In a metallic car-frame, longitudinal center and draft-rigging sills, a transverse bolster-beam upon said sills, and spacing-blocks secured to said center and draft-rigging sills and to said bolster-beam, substantially as described.

5. In a metallic car-frame, a longitudinal center sill, a draft-rigging sill, a spacing-block secured between overlapping portions of said sills, a side sill, and a bolster side piece, se-

cured at its outer end to said side sill and at its inner end to said center sill and spacing-block, substantially as described.

6. In a hopper - bottom car, longitudinal centersills, draft-rigging sills, spacing-blocks between overlapping portions of adjacent center and draft-rigging sills, a car-body having a sloping floor extending above and between said centersills, and a drop-door hinged to between said center sills, substantially as described.

7. In a metallic car-frame, transverse body-bolsters, a longitudinal center sill extending

between said bolsters, draft-rigging sills extending from said bolsters to the ends of the car, and spacing-blocks between the ends of the center sill and the overlapping rear ends of the draft-rigging sills, substantially as described.

In witness whereof I have hereunto signed my name this 6th day of October, 1902.

WILLIAM K. AUCHINCLOSS.

In presence of—

LOUIS A. SHEPARD,
EDWIN C. FARLOW.
